[57] CLAIM

The ornamental design for a wall lamp, as shown and described.

DESCRIPTION

FIG. 1 is a top front perspective view of a wall lamp showing my new design;

FIG. 2 is a front elevational view thereof;

FIG. 3 is a top plan view thereof;

FIG. 4 is a side elevational view thereof, the opposite side being a mirror image;

FIG. 5 is a bottom plan view thereof;

FIG. 6 is a top front perspective view of a second embodiment of my new design;

FIG. 7 is a front elevational view thereof;

FIG. 8 is a left hand side elevational view thereof;

FIG. 9 is a top plan view thereof;

FIG. 10 is a bottom plan view thereof;

FIG. 11 is a top front perspective view of a third embodiment of my new design;

FIG. 12 is a front elevational view thereof;

FIG. 13 is a right hand side elevational view thereof, the opposite side being a mirror image and corresponding to the right hand elevational view of the second embodiment;

FIG. 14 is a top plan view thereof

FIG. 15 is a bottom plan view thereof.
